BY E. J. Silvius,

ATTORNEY.

UNITED STATES PATENT OFFICE.

JOHN H. KOONTZ, OF KIRKSVILLE, INDIANA.

CORN-CUTTER.

SPECIFICATION forming part of Letters Patent No. 673,644, dated May 7, 1901.

Application filed October 26, 1900. Serial No 34,427. (No model.)

To all whom it may concern:

Be it known that I, JOHN H. KOONTZ, a citizen of the United States, residing at Kirksville, in the county of Monroe and State of Indiana, have invented certain new and useful Improvements in Corn-Cutters; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to portable apparatus for cutting off standing cornstalks in the field; and the object is to provide a cheap and simple horse-power cutter, whereby such work may be expedited at the least expense 20 for implements and labor.

Referring to the drawings, Figure 1 is a view in elevation of the right-hand side of the apparatus constructed in accordance with my invention; Fig. 2, a top plan view of the 25 same; Fig. 3 an end view, and Fig. 4 a perspective view, of the cutting-knife; Fig. 5 a rear elevation, and Fig. 6 a front elevation, of the complete apparatus.

Similar letters of reference in the several 30 figures of the drawings designate similar parts.

In construction I form a movable supporting structure comprising sled-runners A A', coupled together suitably, as by means of 35 cross-pieces C and D, and a platform B. The edge *a* of the platform extends somewhat over the runner A from the forward end to a point near the rear end, where it is cut away on a curved line, as at *b*. The rear cross-piece or beam D also extends somewhat over 40 the runner A and supports the rear end of a tongue E, which extends forward therefrom a suitable distance substantially parallel to the edge *a* of the platform, so that a throat 45 F is provided, the extremity of the tongue being curved outwardly, forming a mouth broader than the throat. A tail-board *d* is usually attached to the beam D, extending across the rear end of the platform B and 50 somewhat above the upper surface thereof.

A cutting-knife G, having holes *t t* near the ends thereof, is extended across the rear end

of the throat F diagonally and is secured at one end to the tongue and at the opposite end to the main structure by means of bolts *u u*, 55 extending through the holes *t t*. The cutting edge *p* is preferably formed by beveling the under side, as at *q*, so that the top face of the knife is straight. The knife also acts as a lateral brace for the tongue E, the latter being further reinforced by a brace *e*, attached thereto and also to the beam D at the extremity thereof. In some cases I may provide the tongue E with a runner H to prevent the forward end from being drawn down 60 or from sagging. The knife may, however, be secured in any other suitable manner.

A guide I is formed, preferably of round bar-iron, in a somewhat semicircular contour and provided with feet *ff*, by which it is secured on the top of the platform B, so that the central portion *l* shall be the higher portion thereof, rising a suitable distance above the throat F and leaning over so as to be above the tongue E, near the forward end 75 thereof, situated substantially as shown.

An adjustable guide-arm J is formed, preferably of bar-iron, and has a stem pivoted at its lower end to the tongue E, near the forward end thereof, by a bolt *i* and normally 80 leans rearwardly at an angle oblique to the top of the tongue. The upper part of the guide is bent over, as at *m*, toward the throat and extends over the throat above the knife G at its highest portion *v* and then extends 85 downwardly, as at *n*, at the opposite side of the throat, the extremity of the portion *n* extending over a portion of the guide I. An angle-brace K has one end connected by a pivot-bolt *k* to the tongue E at a suitable position rearwardly from the pivot *i*, and its opposite end is connected to the guide J by a removable bolt *j*. In order to alter the angularity of the guide J, it is provided with one or more bolt-holes *h* near the bolt *j*, so that 90 the latter, together with the upper end of the brace K, may be transferred thereto, thus adjusting the guide J to suit the height of the cornstalks.

In operation a horse may be suitably hitched 100 to the forward end of the sled and the latter dragged on the ground, so that the edge *a* may clear one side of a row of cornstalks, the guide-tongue E drawing all straggling

stalks into the throat, the guide I tending to bend the stalks over against the inner side of the tongue and break bunches, so that the knife G will engage one stalk at a time. The 5 oblique angularity of the knife will cause, as it moves, the stalks to slide along its edge, producing a drawing effect and readily cutting off the stalk, which will be forced forward at its top by the parts *m v n* of the guide 10 *J* until the stalk shall fall upon the guide I and thence upon the platform B, the overhanging portion *l* preventing the stalk from falling into the throat F. The stalks may be taken from the platform by an attendant and 15 tied and shocked or otherwise disposed of, the work being done by this simple means more easily and much more rapidly than by hand-cutting and involving less expense than required in the use of elaborate machines.

20 Having thus described my invention, what I claim, and desire to secure by Letters Patent, is—

1. In a corn-cutter, the combination of the pair of runners, the platform extending over 25 and beyond one of the runners, the cross-piece at the rear end of the runners, the guide secured to said platform at said extending portion thereof, the tongue having the outwardly-curved forward end and secured to said cross-

piece, the knife secured to said tongue and 30 extending to said cross-piece, the brace attached to said tongue and to the outer portion of said cross-piece, the guide-arm pivoted to said tongue, the angle-brace pivoted to said tongue, the removable bolt connecting said angle-brace to said guide-arm, and a plurality of bolt-holes in said guide-arm whereby the same may be adjusted, substantially as set forth. 35

2. In a corn-cutter, the combination of the pair of runners, the platform extending over and beyond one of the runners, the guide extending from said platform above and beyond the extending portion of said platform, the tongue having the outwardly-curved forward end, the runner secured to the forward portion of said tongue, the cutting-knife, the guide-arm pivoted to said tongue, the angle-brace pivoted to said tongue, and the removable bolt connecting said angle-brace to said 45 guide-arm, substantially as set forth.

In testimony whereof I affix my signature in presence of two witnesses.

JOHN H. KOONTZ.
